UNITED STATES PATENT OFFICE.

AUGUSTUS SMITH, OF ROSELLE, NEW JERSEY, ASSIGNOR TO BERGEN POINT IRON WORKS, OF BAYONNE, NEW JERSEY, A CORPORATION OF NEW JERSEY.

CAR.

1,267,931.

Specification of Letters Patent.

Patented May 28, 1918.

Application filed February 27, 1917. Serial No. 151,383.

To all whom it may concern:

Be it known that I, AUGUSTUS SMITH, a citizen of the United States of America, and residing at Roselle, in the county of Union and State of New Jersey, have invented a certain new and useful Improvement in Cars, of which the following is a specification.

My invention relates to cars and particularly to an ordnance car, the special object of my invention being to provide a magazine car adapted to serve a coast defense rifle of the type shown in my co-pending application Serial No. 131,290, although it is to be understood that the present car has utilities other than for the specific purpose mentioned and my invention is not limited to the utilization of the car for ordnance purposes.

In the accompanying more or less diagrammatic drawings,

Figure 1 is a side elevation of the forward end of my improved car utilized as a magazine car and in position to serve a coast defense rifle the breech end of which is shown in this view;

Figure 2 is a plan view of the same showing the car and rifle on a track the curve of which is to the left;

Fig. 3 is a similar view showing the track curving to the right;

Fig. 4 is an end elevation of the car showing the platforms at the car doors lowered into position for putting out ammunition;

Fig. 5 is a plan of the forward end of the car showing the adjustability of the movable telpher rail to various track curvatures; and

Fig. 6 is a similar view drawn to a larger scale.

The car 10, here shown as a magazine car for serving a coast defense rifle, resembles a box freight car, preferably built of steel throughout and having doors 11 in the sides of the same as a standard box freight car, in front of which platforms 12 and 13 (Fig.

4) can be swung down when desired to hold ammunition as it is put out from the car.

The gun 14 is mounted on a gun carriage 15 moving on the same track 16 as the car 10 and the track may be presumed to be a standard gage railway track. Immediately behind the breech of the gun, when the gun is in the horizontal or loading position, is a tray 17 supported on a framework 18, extending from the gun carriage, in which operates a rammer 19 for forcing the ammunition from the tray into the combustion

chamber of the gun in order to load it. The axis of the loading tray 17 is in the prolongation of the axis of the bore of the gun.

Above the car 10 are carried telpher tracks 20 and 21 supported by a suitable framework 22 attached to the roof of the car, on which tracks a main trolley or telpher 23 operates to lift the ammunition from the loading platforms 12 and 13 at the door of the car and then to transport and lower the ammunition onto the loading tray 17 at the breech of the gun. The fixed telpher tracks 20 and 21 supported from the roof of the car are continued beyond the end of the car over the space between the car and the gun carriage by means of the extension track 24, which is supported on a vertical axis 25 so that it can form a continuation of track 20, as shown in Fig. 2, when the operating curve turns to the left, or a continuation of track 21, as shown in Fig. 3, when the operating curve turns to the right. The axis 25 is supported by a stiff framework 26 which is worked out from the car and is substantially a continuation of the frame 22 on top of the car.

It is assumed that the car 10 has space in one end for power generating machinery such as a gasoline engine diagrammatically indicated at 27 driving an electric motor 28 or air compressor 29, or both. The car may also have locomotive means 30 on one or more of its axles so that it can be driven by means of the above mentioned power within itself or by some extraneous source of power.

The car may also be equipped at the ends with standard car couplers 31 for convenient movement in trains with other cars behind a locomotive. To accomplish the handling of the car in trains with other cars it will be understood that the framework 22 and telpher track supported thereon will be bolted or pinned together at 32 so it can be readily taken down or be collapsible in some way so as to reduce the clearance required by the car to the clearance available on ordinary railroads.

The feature that I desire especially to emphasize, however, is the combination of a car with three pieces of telpher track supported over it in such a way that two pieces such as 20 and 21 are rigidly secured when in operation over opposite sides of the car and a third piece, such as 24, is mounted so that it can be connected with either of the rigid pieces 20 or 21 according as the curve on which the car operates turns to the right or to the

left, and where the vertical axis of motion of the movable piece, designated at 25, is so placed with reference to the car and gun carriage that when in operative position it is in the plane of the bore of the gun prolonged so that the telpher 23 operating on it will drop its load of powder and projectile directly in the loading tray 17 at the breech of the gun.

10 Suitable transmission curves 33 and 33¹ for connecting the adjustable piece of track 24 with the fixed pieces of track 20 and 21 are made as part of the fixed pieces as shown in Figs. 2 and 3. It will be understood that the movable track 24 is suitably latched as at 34 to fixed track 20 or 21, when the parts are in operating position.

If the gun and car operated always on a curve of the same radius, a car with a fixed axis of motion 25 with respect to the car, as indicated in Figs. 2 and 3 would suffice for the purposes of my invention. But if the curves on which the gun and car operate are of different radii it becomes necessary to shift the axis 25 with respect to the longitudinal axis of the car so that the movable delivery portion 24 of the telpher track can be made to lie in the plane of the axis of the bore of the gun for any reasonable radius of track. This is shown diagrammatically in Fig. 5, in which the full lines may be taken to represent the minimum radius on which it is considered desirable to operate the car and gun and the dotted lines some 35 larger radius. It is seen that in order to adapt the movable track 24 to the curve of larger radius its axis of motion 25 has to be shifted from *a* to *b*.

Fig. 5 shows the relation when the operating curve turns to the right. If the operating curve turned to the left, as shown in Fig. 2, axis 25 would obviously have to be shifted the other way. Fig. 6 shows this on a larger scale. This position of the vertical axis 25 for track 24 when the operating curve is of some greater radius than the minimum and turns to the right facing the gun, is indicated at *b*. The position of the axis of the movable track for some curve of greater 50 radius when the operating curve turns to the left is indicated at *c*.

The shift of the axis 25 may be accurately governed by moving it in a guideway 35, one portion *x* of which lies in an arc struck from the end of telpher rail 20 as a center, while the other portion *y* of which lies in an arc struck from the end of the other rail 21, so that at whatever point on surface *x* axis 25 may be, track 24 will nevertheless join with the fixed track 20 and similarly if the axis 25 be shifted into the portion *y* of the guide, the end of track 24 will then connect with fixed track 21. It will be understood that suitable means such as clamp 36 for rigidly fastening axis 25 in

the guideway 35 should be provided. The framework of the telpher system may be extended at the outer end 37 to embrace guide 35 and support it properly.

Obviously various modifications of detail of construction and arrangement will readily occur to those skilled in the art without departing from what I claim as my invention.

I claim:—

1. A car suitable for containing materials to be handled, having an overhead track system and telpher for handling said materials, the track consisting of a fixed portion over each side of the car and a swinging extension track supported from the car and connectible with either of the fixed tracks for the operation of the telpher. 75

2. A car suitable for containing materials to be handled having an overhead track system and telpher for handling said materials, 85 the track consisting of a fixed portion over each side of the car and a swinging extension track connectible with either of the fixed tracks at will, in combination with a curved ground track on which the car operates. 90

3. A car suitable for containing materials to be handled, with an overhead track system and telpher for handling said materials, the track consisting of a fixed portion over each side of the car and a swinging track connectible with either of the fixed tracks, in combination with a curved ground track for the car to operate on, together with means for shifting the center of motion of the swinging track to adapt the alinement of the telpher track to the varying curvature of the ground track on which the car operates. 95

4. For use with a track traveling gun having a loading tray at the breech thereof, a novel magazine car having a telpher track adapted to be substantially alined with the gun bore and a telpher traveling thereon to deposit a charge from said car onto the loading tray in position to be shoved into the gun. 105

5. For use with a track traveling gun having a loading tray at the breech thereof, a novel magazine car having an adjustable telpher track adapted to be substantially alined with the gun bore irrespective of the curvature of the track on which the gun is traveled, and a telpher running on said telpher track to deposit a charge from said car onto the loading tray in position to be shoved into the gun. 115

6. For use with a track traveling gun having a loading tray at the breech thereof, a novel magazine car having a pivoted telpher track adapted to swing into substantial alinement with the gun bore and a telpher traveling therein to deposit a charge from said car onto the loading tray in position to be shoved into the gun. 125

7. For use with a track traveling gun hav-

ing a loading tray at the breech thereof, a novel magazine car having fixed lateral telpher tracks and an adjustable extension thereof at one end of the car adapted to be brought 5 into substantial alinement with the gun bore and a telpher thereon to deposit a charge from said car onto the loading tray in position to be shoved into the gun.

In testimony whereof I have signed my name to this specification, in the presence 10 of two subscribing witnesses.

AUGUSTUS SMITH.
